DESIGN FOR A CARRIAGE-PLATE.

No. 38,114.

Specification for Design.

Patented July 3, 1906.

Application filed April 23, 1906, Serial No. 313,357. Term of patent 14 years.

To all whom it may concern:

Be it known that I, WALTER L. WEEDEN, a citizen of the United States, and a resident of Somerville, in the county of Suffolk and State of Massachusetts, have invented a new, original, and ornamental Design for Carriage-Plates, of which the following is a specification, reference being had to the accompanying drawing, forming part thereof.

The drawing shows a perspective view of a carriage-plate embodying my design.

I claim—

The ornamental design for a carriage-plate as shown.

WALTER L. WEEDEN.
